224,845

TRAFFIC MONITORING AND SURVEILLANCE SYSTEM HOUSING

Edward C. Matza, Dallas, Tex., assignor to LTV
Aerospace Corporation, Dallas, Tex.

Filed Oct. 29, 1970, Ser. No. 25,850

Term of patent 14 years

Int. Cl. D29—99

U.S. Cl. D72—1

FIG. 1

FIG. 2

FIG. 3

FIG. 1 is a perspective view of a traffic monitoring and surveillance system housing showing my new design;

FIG. 2 is an end elevational view thereof; and

FIG. 3 is a perspective view of the side opposite that shown in FIG. 1.

I claim:

The ornamental design for a traffic monitoring and surveillance system housing, substantially as shown and described.
